[57] CLAIM

The ornamental design for a pipe hanger, as shown and
described herein.

DESCRIPTION

FIG. 1 is a front elevational view of a pipe hanger
showing my new design, indicating in phantom or
broken lines environmental structure of a pipe supported in
the paper hanger, and the other environmental structure
being support for the pipe hanger to a building structure;

FIG. 2 is a left side elevational view thereof; and,
FIG. 3 is a right side elevational view thereof.

The broken line showing of pipe and a suitable mech-
anism for supporting a pipe hanger to a building struc-
ture is for illustrative purposes only and forms no part
of the claimed design.
